United States Patent Office.

ROBERT WALLACE, OF WALLINGFORD, ASSIGNOR TO THE MERIDEN BRITANNIA COMPANY, OF MERIDEN, CONNECTICUT.

Design No. 4,069, dated May 24, 1870.

DESIGN FOR SUGAR-TONGS.

The Schedule referred to in these Letters Patent and making part of the same.

To all whom it may concern:

Be it known that I, ROBERT WALLACE, of Wallingford, in the county of New Haven and State of Connecticut, have invented a new Design for Sugar-Tongs; and I do hereby declare the following, when taken in connection with the accompanying drawings and the letters of reference marked thereon, to be a full, clear, and exact description of the same, and which said drawings constitute part of this specification, and represent in

Figure 1, a side view, and in

Figure 2, the bow or spring extended.

This invention relates to a design for the spring portion of sugar-tongs and tongs for similar purposes, the object being to make ornamental this part of the article, which has heretofore been but a continuation of the handles.

My invention consists in a narrow straight spring-piece connecting the two handles of the tongs.

A is the handle of one part, and
B the handle of the other part of the tongs, and
may be of any desirable style or form.

C, the spring, is of equal width, extending from
one handle to the other, but narrower than the handle,
the handles themselves appearing to be finished
independent of the spring.

The ornamentation of the spring may be in accordance
with the taste of the manufacturer, or demands
of the public.

I claim as my invention—

The design herein described for the head or spring
of sugar-tongs, consisting of a straight-edged narrow
band, as fully shown in the accompanying illustrations.

ROBERT WALLACE.
